UNITED STATES PATENT OFFICE.

ETTA G. FELTY, OF BROOKLYN, NEW YORK.

SIFTING-SHOVEL.

No. 902,954.

Specification of Letters Patent.

Patented Nov. 3, 1903.

Application filed December 4, 1903, Serial No. 346,218. Renewed September 22, 1903. Serial No. 454,154.

To all whom it may concern:

Be it known that I, ETTA G. FELTY, a citizen of the United States, residing at Brooklyn, in the county of Kings and State of New York, have invented certain new and useful Improvements in Sifting-Shovels; and I do hereby declare the following to be a full, clear, and exact description of the invention, such as will enable others skilled in the art to which it appertains to make and use the same.

My invention relates to new and useful improvements in shovels and more particularly to that class adapted to be used in removing ashes, cinders and the like from stoves and furnaces and my object is to provide means in the bottom of the shovel for sifting the ashes whereby the particles of coal removed with the ashes may be separated from the ashes.

A further object is to provide means for entirely closing the opening in the shovel whereby the same may be employed as a common shovel when desired.

25 A still further object is to provide means for securing the screen and closing device to the shovel.

In the accompanying drawings which are made a part of this application, Figure 1 is 30 a perspective view of my improved shovel complete. Fig. 2 is a top plan view thereof. Fig. 3 is a longitudinal sectional view as seen from line 3—3 Fig. 2. Fig. 4 is a perspective view of the screen removed from 35 the shovel, and, Fig. 5 is a metal strip which is adapted to be inserted over the opening occupied by the screen when it is desired to use the shovel for other purposes.

Referring to the drawings in which similar reference numerals designate corresponding parts throughout the several views, 1 indicates the body of the shovel which may be of the usual or any preferred form in the bottom of which is provided an enlarged 45 opening 2.

Disposed along the lower end and each edge of the opening 2 and spaced from the sides of the body of the shovel are grooves 3 and 4, respectively, which are formed by 50 striking down a portion of the metal and

directing the same in the position shown in Fig. 2 of the drawing thereby forming the grooves in which is adapted to be seated a metal frame 5 in which is disposed a screen 6 which is preferably formed of meshed wire.

In securing the frame to the shovel said frame is directed into the upper ends of the grooves 4 and directed longitudinally therein until the lower end of the frame is seated in the groove 3, thereby providing convenient means for removably securing the frame to the shovel and at the same time by disposing the metal, forming the grooves, in the manner shown, the edges of the opening 2 are reinforced.

In use the shovel is filled with unscreened ashes and by shaking the shovel the finer particles of the ashes descend through the screen while the cinders and unconsumed portions of the coal remain in the shovel thereby enabling me to provide a suitable screen at a minimum amount of cost and by removing the screen and inserting a metal plate 7 in the grooves the shovel may be employed the same as if the opening were not in the bottom thereof.

What I claim is:

The combination with a shovel comprising a body, a bottom portion integral with said body having an opening therein, inwardly facing grooves below and along the sides and the forward end of said integral bottom portion, said grooves being spaced from the sides of the body and formed by bending parts of said bottom portion at the edge of the opening downwardly and outwardly against the under side of the bottom portion and downwardly and inwardly to the vertical plane of the edge of the opening; of a slide and a screen adapted to enter said grooves only one at a time whereby the device may be used as a shovel or a sifter.

In testimony whereof I have signed my name to this specification in the presence of two subscribing witnesses.

ETTA G. FELTY.
